(57) **CLAIM**

The ornamental design for a head and hair accessory hanger, as shown and described.

DESCRIPTION

FIG. 1 is a front perspective view of a head and hair accessory hanger showing my new design;

FIG. 2 shows a left side view thereof;

FIG. 3 shows a right side view thereof;

FIG. 4 shows a front view thereof;

FIG. 5 shows a rear view thereof;

FIG. 6 shows a top plan view thereof;

FIG. 7 shows a bottom plan view thereof;

FIG. 8 shows a rear perspective view thereof; and,

FIG. 9 shows a perspective view of the head and hair accessory hanger in an environment of use.

The broken lines shown in the Figures show portions of the head and hair accessory hanger which form no part of the claimed design.

(Continued)

The broken lines illustrating a wig in FIG. 9 depict environment and form no part of the claimed design.
